UNITED STATES PATENT OFFICE.

ADDISON APPLEGATE, OF LIBERTY, NEW YORK.

STUCCOLIKE SIDING FOR BUILDING PURPOSES.

1,138,069.

Specification of Letters Patent.

Patented May 4, 1915.

Application filed July 21, 1914. Serial No. 852,131.

To all whom it may concern:

Be it known that I, ADDISON APPLEGATE, a citizen of the United States, residing at Liberty, in the county of Sullivan and State of New York, have invented certain new and useful Improvements in Stuccolike Siding for Building Purposes, of which the following is a specification, reference being had to the accompanying drawing, forming a part hereof.

The object of this invention is to provide a substitute for the usual stucco finish of buildings, which shall be equally durable, much less expensive, both in materials and in labor, and practically indistinguishable in appearance. As is well known, the ordinary stucco is mixed somewhat like mortar and is applied with suitable tools to metal lath which has been previously prepared and nailed to the side of the building. Not only does such stucco work involve the very considerable expense of providing and applying the metal lath, but it requires a very considerable quantity of stucco in order that there may be formed a sufficient body to prevent the showing through of the metal lath and to afford a proper amount of clencher to secure the stucco to the metal lath. Even when the stucco is properly applied and in sufficient body dampness frequently penetrates the stucco and causes rusting of the metal lath and dampness in the wall. By the present invention the use of metal lath is wholly avoided, permanent adhesion of the stucco to the base is assured, the penetration of dampness (which causes dry-rot of timber) is prevented, a much smaller quantity of stucco is required, and the labor necessary in applying it is greatly reduced.

The invention will be more fully explained hereinafter with reference to the accompanying drawing, in which it is illustrated, and in which—

Figure 1 is a front view of a portion of a stucco-like siding constructed in accordance with the invention, some of the layers being partly removed in order to show other layers behind them. Fig. 2 is a section on the plane indicated by the line 2—2 of Fig. 1.

In the practice of the invention and the construction of the improved siding there is first provided a fibrous base *a*, which is preferably a fabric of some kind, like a tough paper, which is made water-proof, preferably by saturation with a suitable water-

proof material, such as a preparation of coal tar or asphalt or something of like nature. This base fabric then receives a coating *b*, preferably of a tarry or asphaltic or other pitchy nature, which is both water-proof and strongly adhesive, and while such coating is in a soft or tacky condition, preferably while hot, there is applied a granular coating or layer *c*, preferably of sharp, fine gravel or crushed stone, the purpose of such layer or coating *c*, being to form a binding surface upon the water-proof base, with which the layer of stucco *e* may make a close and permanent union. When the base has been thus prepared it is secured, as by nailing at frequent intervals, preferably with galvanized nails, upon the usual rough board siding. The base may be previously prepared at any convenient point and delivered on the job in sheets or rolls. As it is nailed upon the board siding, strips *d* of water-proof material, like the tarred paper base, are placed under the butt joints of the adjacent sheets of the prepared base *a*, *b*, *c* in order that no dampness may penetrate the finished siding. Thereafter the stucco *e*, a suitable cementitious mixture, colored as desired, is applied to the water-proof base in any suitable manner, as with a brush or with a trowel. The thickness of the coat of stucco is but slight as compared with the thickness of the ordinary stucco and will be varied to suit different conditions of use, being in ordinary cases, perhaps one-eighth of an inch in thickness, more or less. The surface of the stucco coat may receive any desired treatment, like ordinary stucco, being smoothed or brushed or stippled, or treated in any suitable manner.

Obviously, the stucco may be prepared in any suitable manner and of any suitable materials, but on account of its fire-proofing quality and also because it is less likely to crack by expansion and contraction under changes of temperature, it is preferable to employ a stucco which has an admixture of asbestos. Such a stucco may consist of one part of fine sand, six parts of Portland cement, and two parts of powdered asbestos.

I claim as my invention:

A stucco-like siding for buildings which comprises a series of composite sheets each composed of a base of water-proof fabric, a pitchy water-proof coating thereon and a granular coating applied to the pitchy coat-

ing to form a binding surface upon the water-proof base, strips of water-proof fabric disposed respectively under the butt joints of the adjacent composite sheets, and 5 a comparatively thin and continuous surface coating of stucco applied on the granular coating, said composite sheet and strips of water-proof fabric being secured in place

on the building by means of nails placed at frequent intervals.

This specification signed and witnessed 10 this 18 day of July, A. D. 1914.

ADDISON APPLEGATE.
